UNITED STATES PATENT OFFICE.

BENJAMIN HEAP, OF CLIFTON JUNCTION, NEAR MANCHESTER, ENGLAND, ASSIGNOR TO THE ELECTRIC STORAGE BATTERY COMPANY, OF PHILADELPHIA, PENNSYLVANIA, A CORPORATION OF NEW JERSEY.

TREATED WOOD FOR USE IN ELECTRIC STORAGE BATTERIES.

1,073,417.

Specification of Letters Patent. Patented Sept. 16, 1913.

Original application filed October 27, 1908, Serial No. 459,687. Divided and this application filed July 3, 1912. Serial No. 707,627.

To all whom it may concern:

Be it known that I, BENJAMIN HEAP, a subject of the King of Great Britain, and residing at Clifton Junction, near Manchester, England, have invented certain new and useful Improvements in Treated Wood for Use in Electric Storage Batteries, of which the following is a specification.

Wooden separators are an example of the use of wood in electric storage batteries. Provided that wood has been deprived of certain of its constituents its presence in a storage battery is desirable since it has the effect of increasing the capacity of the negative pole plates, especially if they are somewhat worn out, without deleteriously affecting the positive pole plates, and furthermore it is an excellent material from which to make separators. Treatments to which wood was subjected prior to my invention to fit it for use in storage batteries left the wood in such condition that it had to be kept wet in order to prevent it from warping, shrinking, cracking and the like, and to keep the wood wet was objectionable and made it awkward to store, ship and handle the wooden separators.

The object of the present invention is to overcome the difficulty, expense and annoyance of keeping treated wood separators wet and to provide treated wooden separators dry, straight and sound.

The invention, stated in general terms, comprises a dry, straight, sound wooden separator having its natural structure and containing its cellulose and fibrous constituents and constituting an imperforate diaphragm impervious to battery sediment and primarily deprived of such of its constituents as would deleteriously attack lead when subjected to electrolytic action and retaining such of its constituents as beneficially affect a negative pole plate; or in other words, a wooden separator of the general type described in Letters Patent No. 1,000,330, but characterized by the fact that

though dried it is sound and straight and not warped or split or cracked, and can be exposed to the air indefinitely like ordinary untreated wood without injury to it of any kind.

Referring to the drawings, Figure 1, is a plan and Fig. 2, an elevational view of a wooden separator.

In the drawings I have illustrated one type of wood separator *a*, shown as grooved at *b*, upon one side only, but it may be grooved on both sides or flat on one or both sides. The drawing also illustrates the fact that the separator, when dry, after treatment is sound and straight. One way of making a dry, straight, sound, treated wooden separator is described in my pending application, Serial No. 459,687, of which this application may be regarded as a division intended to cover broadly the product without limiting it to that process. The application above referred to eventuated in Letters Patent No. 1,051,580, of January 28th, 1913, and, generally stated, covers the process of treating wood to fit it for use in connection with storage battery plates which consists in digesting or soaking it in an alcoholic solution of a suitable extractive re-agent, washing the wood so treated in alcohol, and drying the washed wood.

What I claim is:

A dry, straight, sound wood separator having its cellulose and fibrous constituents and constituting an imperforate diaphragm impervious to battery sediment and primarily deprived of such of its constituents as would deleteriously attack lead when subjected to electrolytic action and retaining such of its constituents as beneficially affect a negative pole plate.

In testimony whereof I have hereunto signed my name.

BENJAMIN HEAP.
